WHEEL LIFT FOR WHEEL TRUING MACHINE

Edward S. Cisco, Highland, Ind., assignor to Standard Railway Equipment Manufacturing Company, Chicago, Ill., a corporation of Delaware

Application April 14, 1953, Serial No. 348,700

6 Claims. (Cl. 51—236)

This invention relates to a machine for truing wheels of a railway vehicle having flanged wheels which operate on rails under conditions which subject them to considerable abuse, causing flat spots, or other surface irregularities that must be removed and the wheel returned to a condition of roundness.

The present invention is an improvement of the machine shown and described in Patent No. 2,622,378, dated December 23, 1952, and is concerned primarily with a novel means for temporarily elevating the pair of wheels to be trued while the cutting or milling elements of the machine are brought into operating position under the elevated wheels, which is the principal object of the invention. The truing operation is then accomplished in a relatively short time, without the necessity of removing the wheels from the vehicle as at present. The vehicle is thus removed from service for but a short period of time.

Another object of the invention is to provide an arrangement whereby the means for elevating the wheels to be trued simultaneously position the supporting and driving wheels for rotating the wheels to be trued.

Other objects and advantages of the invention will appear in the following description thereof.

Referring now to the accompanying drawings forming part of this application and wherein like reference characters indicate like parts:

Fig. 1 is a plan view of the pit and railroad track assembly with the truing machine installed therein.

Fig. 2 is an enlarged transverse sectional view taken through the pit showing in side elevation the central portion of the truing machine including the wheel lift arrangement, the view being taken along the line 2—2 of Fig. 1.

Fig. 3 is an enlarged longitudinal sectional view taken through the pit and truing machine along line 3—3 of Fig. 1, and illustrating, in broken lines, a railway car truck mounted in proper place for wheel truing.

Fig. 4 is an enlarged, fragmentary, longitudinal section taken on the line 4—4 of Fig. 1.

Fig. 5 is an enlarged, fragmentary, longitudinal section taken on the line 5—5 of Fig. 1.

For purposes of illustration but a single embodiment of the wheel lift arrangement is shown in the drawings and will be described hereinafter, and since the invention is an improvement of the machine shown in the hereinabove mentioned Patent No. 2,622,378 of December 23, 1952, only so much of that machine is herein illustrated and described as is necessary to show the cooperation therewith.

Referring now to the drawings, and particularly to Fig. 1, there is illustrated a wheel truing machine, indicated generally at 30, which is mounted in a pit indicated at 31. A pair of railroad tracks 32, extend away from both sides of the pit, and, extending over the pit, is a track assembly which includes rail members 35—35, 36—36, 37—37 and 38—38, that, together may form a continuous track across the pit. The rail members 36—36 are slidably between

5 two positions, and are shown in the retracted position in

Fig. 1 so as to leave a break in the continuous track to accommodate the wheel truing machine 30. In the other position the rail members 36—36 close the opening and join rails 35—35 to rails 37—37, thus providing a continuous track across the pit.

Transversely of this track and supported on the concrete walls 38' of the pit is a stationary central support that includes a pair of parallel side frame members 40—40, spaced end frame members 41—41A, and an intermediate transverse frame member 42. The frame members 41 and 42 are bored to rotatably receive and support therebetween a shaft 43, upon which is pivotally mounted the entire C-frame assembly which includes a central horizontally disposed portion 44 and upstanding arms 45—45, upon the upper portion of each of which is a centering mechanism 46. Each centering mechanism is constructed and arranged so that it can be raised or lowered vertically simultaneously, and the centers 47—47 20 of which may be moved in or out horizontally so as to be able to engage the axle centers of a vehicle truck, indicated in dotted lines at 48, Fig. 3.

Also mounted in each upstanding arm 45 is a rotary cutter tool which is more or less diagrammatically shown at 50—50, and which is movable up or down substantially vertically with the C-frame assembly so as to occur when desired under the wheels to be operated upon.

All of the above is shown and described in detail in the aforementioned Patent No. 2,622,378, dated December 23, 1952, the details of which form no part of my present invention, except in combination with my improved wheel lift arrangement for such a wheel truing machine, which wheel lift will now be described.

Disposed transversely of the track assembly is provided a rotatable shaft 55, on each end of which is mounted a supporting and driving wheel 56. This shaft 55 is journaled in a pair of spaced arms 57 forming part of an oscillating frame indicated generally at 58, the lower ends of which arms are pivotally mounted on aligned stub shafts 59, each journaled in spaced upstanding walls 60 of a fixed casting 61, anchored on top of a wall 38' forming part of the pit structure.

Keyed to the shaft 55 (Fig. 4) adjacent one arm 57 is a gear 65, which meshes with an idler gear 66, mounted on shaft 59. Gear 66 meshes with pinion gear 68, integrally formed with larger gear 69, which meshes with pinion gear, indicated in dotted lines at 70, rigidly assembled to shaft 71. Shaft 71 extends outwardly and into bearing block 72 mounted upon the casting 61, and inwardly to a gear reducer indicated at 73, also mounted on casting 61, which gear reducer is belt driven by motor 74. Motor 74 rests upon plate 100 dependingly supported by two pairs of rods 101 and 102. Upper ends of rods 102 are anchored in bars 103 which in turn are secured to bottom of casting 61.

A fluid motor is shown at 80 which drives a speed reducer 81, the output shafts 82 of which (extending from opposite sides of said reducer 81) drive the screw jacks 83, there being one of said screw jacks 83 at the outer end of each shaft 82. These screw jacks are identical and but one will be described. As best seen in Figure 5, the outer end of the screw 84 of each screw jack is rigidly assembled in the adjacent end of a clevis 85, the other end of which clevis is bifurcated so as to extend on opposite sides of a lug 87 which projects from and is an integral part of casting 58. The bifurcated ends of the clevis 85 and said lug 87 are bored so as to receive the pin 86 which holds said parts pivotally united.

The fluid motor 80 and speed reducer 81 are rigidly anchored to the flat horizontal central portion of the casting 88, the upstanding end portions 88a of which casting 88 are pivotally mounted (see Fig. 2) to the fixed casting

61, by means of the shafts 89—89, so that when caused to do so, casting 88 may oscillate on shafts 89—89, which are axially aligned. The base of each screw jack 83 is also fixedly mounted on an inclined portion 88a extending outwardly from portion 88a and inwardly from portion 88. Thus when the fluid motor 80 operates the screw jacks, the screws thereof force the arms 57 and casting 58 to oscillate on shafts 59. Since the screw jacks are pivotally mounted to lug 87 of casting 58, which oscillates about shaft 59, the pin 86 will be moved in an arcuate path, causing the screw jacks, the fluid motor 80 and speed reducer 81 mounted on casting 88 to pivot on shafts 89.

While I have shown and described the operation of the wheel lift arrangement as embodying two screw jacks, it is apparent that the unit could be designed to operate with but one, or more as desired.

For anchoring a vehicle truck, as indicated at 48, on the tracks over the machine in the proper position thereon for a pair of wheels thereof to be trued, there is shown in Figure 3 one of a pair of clamps and wheel blocks 90 applied to the opposite pair of truck wheels, which effectively prevents movement of the truck on said rails while the wheels to be trued are being operated upon.

Operation

For purposes of describing the operation of the machine, let it be assumed that the entire machine is lowered in the pit, and the sliding rails 36—36 are in closed position so as to form a continuous rail across the pit. The vehicle or vehicles having wheels to be trued are then brought on rails 32—32 from either direction and brought to rest with the wheels to be trued adjacent to the supporting and rotating wheels 56—56. The clamps and wheel blocks 90—90 are then applied to the opposite pair of wheels in the truck to hold the truck immovable while the wheels are being operated upon. The fluid motor 80 is then actuated, which in turn actuates the screw jacks causing the casting 58, which carries the supporting and rotating wheels 56—56 therewith, to oscillate on shafts 59. The supporting and rotating rollers 56 thus move through an arc having a radius centering on axis of shafts 59. As is best seen in Fig. 3 when wheels 56 move in this arc the periphery of said wheels rises above the plane of the tracks, and when the axes of the vehicle wheels, the rollers and the shafts 59 are in line, the rollers have reached their maximum elevation. When in this position the rollers have forced the vehicle wheels off the track, and the movable track sections 36 are then moved to their open position shown in Fig. 1 to provide an opening in the track assembly under the pair of wheels to be trued. The wheels to be trued are then supported entirely by the supporting and rotating wheels 56—56 and the fluid motor is then reversed until the oscillating casting 58 engages the fixed casting 61, as shown in Fig. 5, and which removes the load from the screw jacks. The truing machine is then raised and brought into operating position. The centering mechanisms 46—46 are then elevated until the center projections 47—47 are located at the level of the centers of the car axle, and then the center projections are moved laterally until they enter the center notches in the ends of the car axle, and the center mechanism is then set in this position. It will be noted that the driving rollers are to one side of a vertical plane through the axes of the axles of the wheels to be trued. The cutter tools 50—50 are now raised until they approach engagement with the tread of the car wheels to be trued. Motor 74 is then actuated which drives the supporting and driving rollers 56—56 which in turn slowly rotate the vehicle wheels to be trued. Motors 95—95 (Fig. 1) are then operated which drive the cutters 50—50. The cutters are then slowly raised causing said cutters to bite into the treads and flanges of the then rotating wheels to be trued. The cutters are then further raised until the de-

sired depth of cut is accomplished. One complete revolution of the vehicle wheels after depth of cut has been accomplished is ordinarily sufficient to true a given pair of wheels, but if not, the cutters can again be adjusted and another cut made.

When the truing operation is thus completed, the centers 47—47 are withdrawn laterally, the wheel truing machine lowered vertically, the fluid motor 80 again actuated which causes the supporting wheels 56—56 to again elevate the wheels which have been trued, the sliding rails then moved to closed position forming a continuous track across the pit, the supporting rollers continued on their arcuate movement until the vehicle wheels are lowered on the track, and the drive rollers positioned therebelow, when the vehicle may be moved off the pit.

I claim:

1. In a device for truing wheels of a railway car while the wheels are mounted on said car and on longitudinally disposed track rails an oscillating frame pivotally mounted in said device; supporting and driving wheels mounted in said frame and rotatable about an axis transversely of the track rails and movable through an arc in the path of the periphery of the wheels to be trued, for engaging and moving said railway car wheels vertically and supporting the same off the track, a second oscillating frame mounted in said device, and power means on said second mentioned frame operatively connected to said first mentioned oscillating frame for oscillating the same and causing said supporting and driving wheels to raise said wheels to be trued off said track.

2. In a device for truing wheels of a railway car while the wheels are mounted on said car and on longitudinally disposed spaced track rails having a slideable rail segment adapted to close the space between said track rails an oscillating frame pivotally mounted in said device, supporting and driving wheels mounted in said frame and rotatable about an axis transversely of the track rails and movable through an arc in the path of the periphery of the wheels to be trued, for engaging and moving said railway car wheels vertically and supporting the same off the track so that the slideable rail segment may be moved, and power means on said frame operatively connected to said supporting and driving wheels for moving the same through said arc and raising said wheels off said track.

3. In a device for truing wheels of a railway car while the wheels are mounted on said car and on longitudinally disposed track rails; an oscillating frame, supporting and driving wheels, carried by said oscillating frame, and movable through an arc in the path of the periphery of the wheels to be trued, for engaging and moving said railway car wheels vertically and supporting the same off the track, a second oscillating frame, and power means on said second oscillating frame operatively connected to said first mentioned oscillating frame for oscillating same and causing said supporting and driving wheels to raise said wheels to be trued off said track.

4. In a device for truing wheels of a railway car while the wheels are mounted on said car and on longitudinally disposed spaced track rails, a fixed frame, an oscillating frame having spaced parallel arms pivoted at their lower ends to said fixed frame for oscillating movement in relation therewith, a supporting and driving wheel mounted on each arm in axial alignment and movable with the oscillating frame into engagement with the periphery of the wheels to be trued, and for raising said car wheels off the track, a second oscillating frame, and power means carried by said second oscillating frame and operatively connected with said first mentioned oscillating frame to oscillate same.

5. In a device for truing wheels of a railway car while said wheels are mounted on said car and on longitudinally disposed track rails, a fixed frame, an oscillating frame, pivotally mounted on said fixed frame so as to oscillate

in relation therewith, supporting and driving wheels carried by said oscillating frame for engaging and raising said car wheels off the track, power means operatively connected to said supporting and driving wheels to rotate the same and thereby the wheels to be trued, a second oscillating frame and power means, carried by said second mentioned oscillating frame and operatively connected to the first mentioned oscillating frame to oscillate same.

6. In a device for truing wheels of a railway car while said wheels are mounted on said car and on longitudinally disposed track rails: a fixed frame disposed below the rails and transversely thereof, an oscillating frame pivotally mounted to said fixed frame, supporting and driving wheels mounted on said oscillating frame and movable through an arc in the path of the periphery of the wheels to be trued for engaging and raising said wheels to be

trued off the track, an oscillating casting pivotally mounted to said fixed frame, screw jacks secured adjacent the base end to said oscillating casting, and pivotally mounted at the screw end to said oscillating frame, to cause the oscillating frame to oscillate, power means mounted upon the oscillating casting for operating said screw jacks, and power means supported by said oscillating casting for rotating the supporting and driving wheels.
